W. Schwab's Design for Knitted Cap.

PATENTED
OCT=5 1869

Witnessed.

W. Knapp,
J. W. Mahler

Inventor:

William Schwab

United States Patent Office.

WILLIAM SCHWAB, OF NEW YORK, N. Y.

Design No. 3,706, dated October 5, 1869.

DESIGN FOR A KNITTED CAP.

The Schedule referred to in these Letters Patent and making part of the same.

To all whom it may concern:

Be it known that I, WILLIAM SCHWAB, of the city, county, and State of New York, have invented a new and original Design for Knitted Cap; and I do hereby declare the following to be a full, clear, and exact description thereof, which will enable those skilled in the art to make and use the same, reference being had to the accompanying drawing, forming part of this specification.

The drawing represents a side view of my cap.

This design relates to a knitted cap, composed of a tubular neck and shoulder-piece, and curved head-piece, with an opening for the eyes and other parts of the face, the whole being ornamented by a border round the edge of the opening for the face, and also round the bottom edge of the tubular neck and shoulder-piece.

In the drawing—

The letter A designates the tubular neck and shoulder-piece, which is joined to the curved head-piece B, leaving an opening, C, for the eyes and other parts of the face.

The edge of this opening is ornamented by a border, a, and the edge of the tubular neck and shoulder-piece by a border, b.

What I claim as new, and desire to secure by Letters Patent, is—

The design for a knitted cap, as shown and described.

WILLIAM SCHWAB.
